(57) **CLAIM**

The ornamental design for a table with arcuate leg structure, substantially as shown and described.

DESCRIPTION

FIG. 1 is a top pictorial view of a table with arcuate leg structure showing our new design;

FIG. 2 is a side elevation of one side of the table of FIG. 1, with the opposite side being a mirror image thereof;

FIG. 3 is a top plan view thereof; and,

FIG. 4 is a bottom plan view thereof.

1 Claim, 4 Drawing Sheets
